LISTENING HELMET FOR SOUND LOCATORS

Frank R. House, Baldwin Harbor, N. Y., assignor
to Sperry Gyroscope Company, Inc., Brooklyn,
N. Y., a corporation of New York

Application July 29, 1939, Serial No. 287,236

3 Claims. (Cl. 181—26)

This invention relates, generally, to apparatus for locating aircraft or other moving targets under conditions of poor visibility, as at night or during fog, and the invention has reference, more particularly, to improvements in sound locator receivers and associated apparatus of the type disclosed in my prior Patent No. 2,159,481, dated May 23, 1939.

Inasmuch as sound location is always conducted in an ambient of audible noise, the sound of an aircraft or other object to be located cannot be made audible until its total sound level at the listening station or some part of its sound spectrum reaches a level approximating that of the ambient. A reduction in ambient sound results in increased listening range, and hence soundproofing of sound locator receivers to reduce ambient sound in the receiver is important. Ambient sound may be divided into two classes, i. e., general background and local noises, the first consisting of sound that is generated at a distance from the receiver and is air borne to the latter, and the second consisting of sound generated within the receiver assembly and transmitted directly by vibration to the receiver sound track.

The present invention is a continuation in part of my prior application, now Patent No. 2,199,404, for Sound Locator Apparatus, dated May 7, 1940, and pertains particularly to the listening helmets worn by the listeners who operate the sound locator. The helmets are especially designed to exclude all background noises from the ears of the listener so that only the sound arriving through the tubes connected with the sound locators is heard by the listener. To this end, metal plates are provided around each ear piece to support the transmitting tubes and to fit the head tightly around the ear so as to exclude outside noises. The metal plate is padded on both sides with soft pliable material of the helmet, such as soft leather or rawhide, and an annular padded portion placed between the head and the metal plate around the ear.

Further objects and advantages will become apparent from the following specification.

Referring to the drawings, showing the preferred form of my invention,

Fig. 1 is a perspective view, in elevation, taken from the rear of the complete sound locating apparatus.

Fig. 2 is a side elevation of the helmet as worn by a listener, with the same disconnected from the tubes normally connecting it to the listening horns.

Fig. 3 is a section through the helmet, on an enlarged scale, taken approximately on line 3—3 of Fig. 2.

Fig. 4 is a front elevation of one of the metal plates of the helmet which surrounds each ear.

Fig. 5 is a transverse section taken approximately on broken line 5—5 of Fig. 4.

Fig. 6 is a side elevation of one of the adjustable ear pieces or tubes of the helmet.

Referring now to the said drawings, the sound locator apparatus comprises a suitable arrangement of listening or sound collecting receivers or horns 1, 2 and 3 mounted for both turning in azimuth and tilting in elevation, the horn 2 being a common horn in that it cooperates with horn 1 in making elevation determinations and with horn 3 in making azimuth determinations. The horns or receivers 1, 2, 3 are carried by arms 4, 5, 6 that are detachably secured to a common cross shaft 8 which is, in turn, mounted for turning in elevation on a head 7 by means of an elevation handwheel 9 connected through gearing 10 for turning the horns 1, 2, 3. Head 7 contains the sound lag correction and other apparatus forming no part of the present invention, and is mounted for turning in azimuth on a pedestal 8' by means of an azimuth handwheel (not shown). Pedestal 8' is mounted upon a circular platform 12 that is supported in a level position by adjustable leveling screws 13.

For leading the sound received from the horns to the listeners' ears, I preferably employ complete helmets 14 and 15 for the train operator and the elevation operator, respectively, the former being shown as connected through tubes 16 and 17 to the horns 2 and 3 and the helmet 15 being shown as connected through tubes 18 and 19 to the horns 1 and 2. Said tubes are of soft rubber so as not to transmit vibrations to the helmets. Each helmet is preferably made of leather and is strapped on the head by several cross straps 20, 21 and 22 and by a chin strap 23, said straps extending between pieces of rawhide 24 secured to the helmet around each ear piece. The ear pieces are mounted in the sides of the helmet, so that the helmet may be adjusted by means of the straps to accurately position the ear pieces and hold them comfortably in place.

The ear piece structure is shown in section in Fig. 3 and comprises a plate 25 of sheet material, such as aluminum, of a generally elliptical contour, as shown in Fig. 4, but dished or cupped so that the outer edge fits the contour of the head or skull around the ear, while sufficient space is allowed in the middle for the ear. Fig. 3 shows

a cross section of the plate in the vertical plane, while Fig. 5 shows a transverse section. This plate is provided with a central hollow boss or extension 26 which is threaded interiorly for a short distance, as at 27. Into said threaded portion is screwed the ear piece proper 28, shown in elevation in Fig. 6. This comprises a short metallic portion 29 having an outer knurled collar 30 and provided with threads 31 to screw into the aforesaid threads 27. On its forward end I provide a short tube or thimble 32, preferably made of plastic or insulating material, such as "Bakelite" or rubber, and provided with a rounded end 33 which is designed to fit into the concha of the ear. The inner diameter of this tube is kept substantially unrestricted so as to impose no baffling or attenuating effect in the sound track. In order to fit into the concha of the ear, the diameter is also made materially less than the diameter of the ordinary ear piece of a telephone receiver which fits over the outer ear, but at the same time is made materially greater than the diameter of the usual ear pieces on stethoscopes which fit into the entrance to the auditory canal. An inner diameter of somewhat less than an inch and an outer diameter on the order of an inch have been found satisfactory for this purpose. A sound locator helmet must be worn for long periods of time and must therefore be comfortable to the wearer, and ear pieces of the type which fit into the auditory canal not only become extremely uncomfortable after short wear, but also the sound track passage therethrough is so restricted as to interfere with the maximum reception. Likewise, the larger ear pieces similar to a telephone receiver also become uncomfortable and, in addition, do not exclude extraneous noises effectively. By screwing the member 28 in and out, it may be brought into comfortable engagement with the ear so as to further exclude outside noises. The interior of the tube 29 may be provided with a spring ring 34 to detachably hold in place a connecting tube or fitting 35 on the end of one of the rubber tubes 16. Hence the user may fit the helmet on the head in the desired position before connecting the tubes leading to the sound locators, and then when the helmet is fitted to his taste, fittings 35 may be inserted into the tubes 29 on each side of the helmet and held in place by the springs 34 with their inner ends against collar 31 within tubes 29.

An elliptical pad 36 is stitched or otherwise secured to the helmet around the edge of each plate 25 to fit tightly against the head. This serves to shut out local noise, relieves the ear of pressure, and provides a dead air space 41 around the ear between the head bones adjacent the ear and the plate 25. The metal plate thus cuts off local noise by reason of its mass, aided by the leather covering of the helmet on both sides thereof, at 39 and 40, which damps out vibrations of the plate. The dead air space at 41 between the head and plate is also a valuable aid toward this end.

In using the helmet, the operator places the same upon his head with the tubes 16 and 17 disconnected and inserts his forefingers into the

central apertures of tubes 29 and shifts these tubes 29, and hence the ear pieces of the helmet, if necessary, so as to align the tubes with the ear conchas. He thereupon turns the conduits or tubes 29 so as to thread these tubes inwardly or outwardly to bring the ear pieces 32 into comfortable position within the ear conchas. When he desires to listen in at the apparatus, it is merely necessary to plug the nipple plugs 35 of the tubes 16, 17, or 18, 19, as the case may be, into the helmet ear piece sockets, and is assured of proper hearing inasmuch as these tubes are aligned directly with the centers of the listener's ears, the projection of members 32 into the ear conchas serving to eliminate echo effects.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim and desire to secure by Letters Patent is:

1. In an ear engaging head piece for sound locators, a metallic dished oval plate arranged to overlie the ear of the user, said plate having its convex side positioned outwardly and being of such curvature as to substantially conform to the head surrounding the ear while leaving a dead air space between the head and the inner surface of said plate, said plate also having a central aperture, a sound conveying tube of uniform inner diameter throughout its length, an open-ended ear engaging tube connected with said sound conveying tube and having substantially the same inner diameter as said sound conveying tube, said ear engaging tube being adjustable within said aperture toward and from the ear concha to suit the user's ear and operating conditions.

2. An ear engaging head piece as defined in claim 1, wherein a substantially annular padding is provided adjacent the outer periphery of the inner concave surface of said dished plate for engaging the head to shut off extraneous noises, said plate inner surface being covered with a layer of sound absorbing material.

3. In a head piece for sound locators, a pair of ear pieces each comprising a dished plate providing an inner ear receiving cavity and having a central aperture, padded sound absorbing material secured adjacent the outer periphery of the concave inner surface of said plate to fit around the outer ear, an ear engaging tube having a substantially unrestricted opening and of about the diameter of the ear concha, said tube being adjustably movable in said plate aperture toward and from the ear, whereby its inner end may be adjusted to suitably engage the ear concha or moved outwardly therefrom, said plate having sound absorbing material on its inner and outer surfaces, and a separable flexible sound track tube adapted to connect said first mentioned tube to a sound receiver.

FRANK R. HOUSE.
